UNITED STATES PATENT OFFICE.

MELVILLE CLARK, OF CHICAGO, ILLINOIS.

DUPLEX TRACKER-BOARD FOR AUTOMATIC MUSICAL INSTRUMENTS.

No. 921,639.

Specification of Letters Patent.

Patented May 11, 1909.

Application filed May 31, 1907, Serial No. 376,498. Renewed May 25, 1908. Serial No. 434,877.

To all whom it may concern.

Be it known that I, MELVILLE CLARK, a citizen of the United States, residing at Chicago, in the county of Cook and State of Illinois, have invented new and useful Improvements in Duplex Tracker-Boards for Automatic Musical Instruments, of which the following is a specification, reference being had to the drawings forming a part thereof.

10 The purpose of this invention is to provide an improved construction of tracker board and connections of the ducts thereof for the purpose of adapting the instrument provided with such tracker board, when suitably constructed in other respects, to be operated for any one of the following purposes by the different forms of controllers specified, to wit:—1. For playing within a limited range, say 58 notes, by means of a 15 single set of playing devices of that number when controlled by a 58-note traveling sheet. 2. For playing in a similar manner a greater range, say 65 notes, when controlled by a 65-note sheet. 3. For playing 20 in a similar manner a maximum range of, say 88 notes, when controlled by an 88-note sheet, each of the three controller sheets thus far mentioned being cut to the same scale hereinafter referred to as the "wider" scale. 4. For playing up to the maximum range of 25 88 notes when controlled by an 88-note sheet cut to a narrower scale. 5. For playing up to any desired range, as 70 notes, with one set of playing devices playing, for example, 30 an accompaniment, and simultaneously playing, by an independent set of playing devices, a solo or melody within a range of notes for which apertures in the tracker board, on the narrower scale, can be provided in addition to the 70 first mentioned on such narrower scale within the total 35 length of tracker board required for 88 notes of the wider scale.

Assuming, for example, a so-called wider scale on the basis of one-sixth inch for each note, making, for 88 notes, a total length from center to center of the extreme apertures of $14\frac{1}{4}$ inches, there will be room within the same length for a parallel set of 40 tracker mouths on a scale of, say $\frac{1}{8}$ inch, for 116 notes of which 70 apertures at the middle part may be employed for accompaniment and the remaining 46—23 at each end—for solo or melody playing. It will be evident that the scope of the invention is not limited to any particular number of notes,

or tracker ducts for the same, in the several groups. Perforated controlling sheets are now commonly cut for 58 notes, for 65 notes and for 88 notes, and it is also common to 60 cut upon a narrower scale 88 notes in the width of paper required for 65 notes of the wider scale, and the numbers used in the above statement and hereinafter in this specification are to be understood as representing any convenient groups which the conventional or standard manufacture of automatic instruments may require.

The invention consists in the features of construction hereinafter described and illustrated in the drawings as indicated in the claims.

In the drawings:—Figure 1 is an edge view or front elevation of a tracker board and parts associated therewith embodying 75 this invention. Fig. 2 is a top plan, and Fig. 3 is a bottom or inverted plan of the same. Fig. 4 is a rear edge elevation of the same. Fig. 5 is a section at the line 5—5 on Fig. 2, showing the parts in position for shutting off 80 all the ducts of both sets,—that is, for preventing playing. Fig. 6 is a section at the line 6—6 on Fig. 4 transversely through the tracker board at one end of the several valve boards showing diagrammatically the connection from the tracker board to the pneumatic action. Fig. 7 is a vertical longitudinal section through the tracker board and valve boards showing the parts adjusted for playing 58 notes by use of the set of ducts 85 cut on the wider scale. Fig. 8 is a view similar to Fig. 7 showing the parts adjusted for playing 65 notes by means of the wider spaced scale. Fig. 9 is a similar view showing the parts adjusted for playing 88 notes 90 with the wider spaced scale. Fig. 10 is a similar view showing the parts adjusted for playing 88 notes with the narrower set of ducts. Fig. 11 is a similar view showing the parts adjusted for playing a melody within 100 a range of 46 notes by means of an independent set of playing devices, and the accompaniment within a range of 70 notes by means of a separate set of playing devices, both sets being controlled by connection with 105 the narrower spaced set of ducts. Fig. 12 is a detail plan view of one end of the tracker board showing a graduated dial and operating-handled index finger for adjusting the parts for the different uses. Fig. 13 is a sectional view showing diagrammatically as to 110 relative position, but graphically in the other

respects, a modification in which the tracker mouth piece is separate from the tracker duct board, the connections being made by flexible tubes, section being made transversely with respect to the tracker mouth piece and duct board.

The tracker board comprising the tracker mouthpiece, 1, and the remainder which may be distinguished from the mouth-piece as the "tracker-duct-board", 1^a, may be a unitary structure, as in Figs. 1 to 9 inclusive; or for certain purposes the tracker mouth-piece may advantageously be separate from the tracker-duct-board and connected with the latter by tubes, as shown in Fig. 13. This invention will be described primarily with reference to the unitary form of the tracker board.

The tracker mouth-piece has two separate series of duct mouths, the upper or rear series, A, being cut on a narrower scale, as, for example, one-eighth of an inch between centers of duct mouths. The lower or forward series, B, parallel with the first, has the duct mouths spaced on a wider scale, or substantially one-sixth of an inch between centers of the duct mouths. The two series of duct mouths, A and B, occupy substantially the same distance lengthwise of the tracker mouth-piece. From each series the ducts are led out through the side of the tracker board, those of the series, A, being led out through the upper or rear side of the board, and those of the series, B, being led out through the lower or forward side; and in order to obtain adequate space for connection with the customary tubes, 2, 2^a and 3, (leading from the upper and lower series respectively) the laterally outleading ends of the ducts are distributed in staggered arrangement in three groups, so that there are formed three rows of mouths, the intervals between consecutive mouths of each row being thus rendered nearly double the distance between centers of the duct mouths themselves in the tracker edge. I do not limit myself to any particular number of rows or to this particular expedient for obtaining space for the tubes. I adopt it and show it in this instance because it is a familiar and practical expedient for obtaining space for this or any other purpose.

Upon the lower face of the tracker-duct-board there is applied a valve bar, 4, having apertures corresponding to and adapted to register with the out-leading duct mouths of the lower series, B,—that is to say, when the said valve strip is suitably located for such registration,—said strip being adapted, however, by displacement from registering position to act as a valve for closing all said duct mouths. The apertures of this valve bar, for convenience of reference, are divided into three groups,—a middle group corresponding to the 58 middle notes or a

total range indicated by reference character, 4^a; lateral groups next outside of this middle group corresponding to the seven additional notes up to 65,—that is to say, three at one side and four at the other,—indicated by the reference character, 4^b, and extreme outer groups corresponding to the remaining 23 notes from 65 up to 88,—that is to say, eleven at one side and twelve at the other,—indicated by the reference character, 4^c. To the middle set, 4^a, the flexible tubes, 3, are connected, and it may be understood that these tubes lead to the primary pneumatics of a pneumatic action conventionally indicated at C for operating playing devices in a well understood manner, neither said primary pneumatics nor any portion of said pneumatic action being illustrated in detail in the drawings. Upon the outer,—that is to say, the lower,—face of the principal valve bar, 4, there are applied over the right-and-left end portions secondary valve bars, 5, 5, which are connected together by a tie bar, 5^x, so as to operate as an integral or unitary device. These valve bars, 5, have apertures corresponding and adapted to register with the apertures, 4^b and 4^c, of the principal valve bar, 4, and for convenience of reference are indicated in two groups 5^b, corresponding to the apertures, 4^b and 5^c, corresponding to the apertures, 4^c, of the valve bar, 4. To the apertures, 5^b, the flexible ducts, 3, are connected for leading to the primary pneumatics of the pneumatic action conventionally shown at C. To the outer,—that is, the lower,—side of the supplemental valve bars, 5, covering the entire group of ports, 5^c, there are applied secondary valve bars, 6, 6, having ports, 6^c, corresponding to and registering with the ports, 5^c, of the valve bars, 5, and having the flexible ducts, 3, leading from them at the outer side to the pneumatic action, C, thus completing the entire set of flexible ducts, 3, from the tracker ducts of the wider spaced set, B.

It will be seen that the valve bars, 4, 5 and 6, may be so adjusted relatively to each other and to the tracker bar as to open communication through the entire set of ducts, 3; also that when so set, the displacement longitudinally of the valve bar, 6, a distance a little more than the diameter of the apertures, 6^c and 5^c, will cut off communication of the outer end portions of the ducts down to number 65, cutting off, that is to say, twelve ducts at one end and eleven ducts at the other end; and that similar longitudinal displacement of the valve bars, 5, bringing their apertures, 5^c, back into registration with the apertures, 6^c, but out of registration with the apertures, 4^c, will cut off the ducts between 58 and 65, leaving only the middle group of 58 ducts in registration, and that similar displacement lon-

5 longitudinally of the valve bar, 4, bringing its ducts back into registration with those of the valve bars, 5 and 6, will cut off all the ducts of the entire series, B. The means for thus moving the several valve bars will be hereinafter described.

Upon the upper or rear surface of the tracker bar there is mounted a principal valve bar, 7, corresponding to the principal valve bar, 4, having apertures adapted to register with, and upon displacement to cut off, the outleading mouths of the tracker ducts of series A. For convenience of reference, these apertures are referred to in three groups,— 15 7^a being a group of 70 at the middle part of the total range, and 7^b being two groups, one at each end of said middle group, including 9 in each group,—a total of 18,—making, together with the middle group, 88 notes, 20 and having, therefore, a total range equal to the range of the entire set of ducts, B; thirdly, the outer groups, 7^c, 14 each,—28 in all,—being the excess of the number of the series of ducts, A, above the number of series 25 B. Outside,—that is, upon the upper surface,—of the principal valve bar, 7, there are, covering the end portions of said bar, two similar secondary valve bars, 8, 8, having apertures, 8^b and 8^{bx}, for registering with 30 the apertures, 7^b, of the valve bar, 7, and having outside of these groups groups of apertures, 8^c, for registering with the apertures, 7^c, of the valve bar, 7. Flexible tubes, 2, are connected to the apertures, 7^a, of the 35 valve bar, 7, and to the apertures, 8^b, of the valve bar, 8, and are joined to the corresponding tubes, 3, leading from the corresponding 88 ducts of the series B, and thereby connected to the same pneumatic 40 action, C. Only one of the two series of ducts, A and B, it will be understood, is designed to be in service at a time, each being cut off when the other is operative, as more particularly hereinafter explained. From 45 the ducts, 8^c and 8^{bx}, flexible tubes, 2^x, lead to the primary pneumatics of an independent pneumatic action, conventionally shown at D, for operating an independent set of playing devices (not shown).

50 It will be seen that the valve bar, 7, may be adjusted so that all its ducts will register with the corresponding mouths of the tracker ducts of the series A, and that when it is so adjusted the valve bars, 8, may be so adjusted upon it as to register the ducts, 8^b, with the ducts, 7^b, and thereby with the corresponding mouths of the tracker ducts, A, and that when thus adjusted the entire 88 tubes, 2, will be in communication with the 55 middle 88 tracker ducts, and that a controller sheet cut on the narrow scale for 88 notes would coöperate with these middle 88 ducts of the series A for playing, precisely as a similar controller sheet for 88 notes cut 60 to the wider scale will coöperate with the

entire series B when the valve bars upon the lower side are adjusted to bring that series of ducts into action. It will be noticed by reference to the drawings that the apertures, 8^c and 8^{bx}, are so situated that they do not 70 register with the apertures, 7^b, when the apertures 8^b are registered with the corresponding apertures, 7^b, and that therefore whenever the valve bars, 7 and 8, are adjusted for playing 88 notes under the control 75 of a controller sheet cut for the narrower scale, the playing devices connected with the tubes, 2^x, will be out of service. But it will be observed that by moving the valve bars, 8, longitudinally to displace the ducts, 8^b, from registration with the ducts, 7^b, the ducts, 8^{bx} and 8^c, come into registration with the ducts, 7^b and 7^c, respectively, and that when this adjustment is made while the bar, 7, is adjusted for registering all its apertures 80 with the entire series of tracker ducts A, not only will the 70 middle ducts of the series A be in communication through the tubes, 2, with the same set of playing devices which may, with proper adjustment, be operated from ducts of series B, but also the remaining 46 ducts, 23 at each end, of series A, will be in communication through the tubes, 2^x, with the second set of playing devices 85 designed for playing the melody or solo, and that with a controller sheet cut to the narrower scale with 116 lines of apertures, 70 at the middle portion being devoted to the accompaniment and 23 at each end to the melody or solo, the instrument equipped 90 with the tracker devices shown and having two such sets of playing devices will be adapted to play with one set of playing devices the accompaniment, and with the other set the melody or solo, each part of the music being controlled by the corresponding 95 part of the 116 note controller sheet.

For operating the valve bars, 4, 5, 6, 7 and 8, any convenient mechanical expedients 100 may be employed, and those illustrated are merely suggestive, and the description of them is not intended to be restrictive. Each bar may be provided with a spring, 10, tending to hold it at one limit of its range 105 of movement. (The two bars 5, 5, 6, 6, 115 8, 8, of each pair, being rigidly connected, are treated in this description as one bar.) Such springs being arranged to thrust the bars normally to the left hand, for example, there may be mounted at that end in the 120 tracker or in fixed relation thereto a rotary shaft, 11, having cam disks, one for each valve bar, in the planes of said bars respectively.

All the disks, 12, 13, 14, 15 and 16, are 125 fast on the shaft, 11, and at one position of the shaft they permit all the valve bars to stand at the extreme left-hand position to which they will be forced by their respective springs, as seen in Fig. 1, the position 130

of the valve bars respectively at this position of the cam shaft being indicated in Figs. 1 and 5. The disk, 12, is so formed that upon rotation of the shaft through a certain angle, say 60 degrees, it thrusts the bar, 4, into position for registration of its apertures with those of series B of the tracker board, and from that point, the cam disk being concentric, any further rotation does not displace the valve bar from that position, but holds it thus registered. At this position the 58 middle apertures of series A will be in service, the movement of the bar, 4, having effected the registration of all its apertures with the tracker bars, but thereby having cut off registration of its apertures, 4^b and 4^c, with the next bar, 5. The cam disk, 13, is so formed that the portion which is operative against the valve bar, 5, during the first 60 degrees of rotation with the cam shaft is concentric and does not move that valve bar, but the next 60 degrees is eccentric to an extent sufficient to thrust the bar, 5, one step longitudinally so as to restore the registration of all its apertures with those of the bar, 4, and thereby with the tracker bar, thus bringing into service the two groups of notes, seven in all, at the opposite ends of the middle group of 58. The cam disk, 14, is formed concentric for the first 120 degrees of its periphery in contact with the valve bar, 6, so that that bar is not moved during the actions thus far described, but in the next 60 degrees of this disk its eccentricity is such as to thrust the bar, 6, longitudinally to register its apertures with those of the bar, 5, thereby bringing into service all the tracker ducts of series B. During all this action the cam disks, 15 and 16, have been operating by concentric portions of their periphery against their respective valve bars, 7 and 8, so that said valve bars have remained in position cutting off communication of the entire series A of tracker ducts. In order to bring this set of ducts into service when the instrument is being used with a controller sheet cut to the narrower scale, the cam shaft will be rocked back to starting point, thereby closing all the ducts of series B. Its movement through 60 degrees to the left from the starting point causes the first eccentric portion of the cam disk, 15, operating against the valve bar, 7, to thrust it longitudinally for registration of its ducts with the corresponding mouths of the tracker ducts of series A; and in this movement, as already explained, not only will the 70 apertures of the group, 7^a, be brought into service, but also the 18 apertures, nine at each end, of the group 7^b, will be brought into registration, not only with the mouths of the tracker ducts; but also with the apertures, 8^b, of the valve bar, 8, so that by this adjustment the 88 middle ducts will be

brought into service for playing 88-note music cut to the narrower scale, the remaining 46 ducts—23 at each end—being covered by the valve bars, 8, whose apertures, 8^a and 8^b, will be out of registration with the corresponding apertures, 7^b and 7^c, of the valve bar, 7. In the next 60 degrees rotation of the cam shaft to the left the eccentric portion of the cam disk, 16, operating against the valve bar, 8, will thrust it longitudinally so as to bring its apertures, 8^a and 8^b, into registration with the corresponding apertures, 7^c and 7^b, of the valve bar, 7, cutting off registration of the apertures, 8^b, with the corresponding apertures, 7^a, of said bar, 7, thus leaving in service in connection with one set of playing devices for the accompaniment the 70 middle ducts of the series A, and bringing into service in connection with the independent action the 23 notes at each end—46 in all—from which the flexible pipes, 2^x, lead to such independent action. A dial plate, 18, is provided, over which an index finger, 19, on the shaft, 11, moves in the rocking of the shaft to the various positions stated, and at the several points at which it should be halted for registration for the several purposes above stated, the particular purpose or result effected by its setting at such points is noted on the dial, and the operator is thus instructed as to the adjustment to make for each of said purposes.

For the purposes of the various adjustments of the valve-bars on the duct board on which they are mounted, it is obviously immaterial whether or not that duct board is the tracker board; that is, whether its edge is the mouth-piece over which the controller sheet travels for co-operation with the ducts. And for these purposes, such duct board may be at any other position, provided its ducts are connected with the duct mouths of the tracker mouth-piece. In Fig. 11, I have shown the tracker mouth, E, as a part distinct from the tracker-duct-board, F, the connection of the tracker duct mouths to a tracker duct of the tracker-duct-board being made by flexible tubes, G. The several valve bars in this form are identical in operation and relative position with those of the other form, differing only in size, the advantage of thus separating the tracker mouths and the tracker-duct-board being that the latter can be extended, if desired, to the full length of the manual or of the pneumatic action chamber. No further description of these forms is therefore necessary; but it will be noticed that the necessity for mounting the valve-bar-operating devices on the tracker-duct-board is avoided when said duct board is separated from the tracker mouth-piece, so that the latter can be adjusted longitudinally alone for such purposes as transposition.

I claim:

1. In an automatic music playing instrument, in combination with a tracker duct board having two series of ducts leading to different areas of the board's surface; separate valve bars for the two series of ducts having apertures adapted to register with the ducts at said areas respectively; flexible tubes connecting a definite number of apertures of one valve bar with the corresponding apertures of the other bar and with a pneumatic action, said valve bars being adapted to be moved for cutting off and opening communication of the respective series of ducts with said pneumatic action.

2. In an automatic music-playing instrument, in combination with the tracker duct boards having two series of ducts of different number leading to different areas of the board's surface; separate principal valve bars for the two series having apertures adapted to register with the ducts at such areas respectively, and corresponding in number to the respective series of ducts; flexible tubes connecting a definite portion of the whole number of the apertures of the valve bar having the greater number with the corresponding apertures of the other bar and with a pneumatic action, said valve bars being adapted to be moved for cutting off and opening communication of the respective series of ducts with said pneumatic action; a secondary valve bar having apertures adapted to register with the remaining apertures of the principal valve bar having the greater number, and flexible tubes leading from the apertures of said secondary valve bar to a second pneumatic action.

3. In an automatic music playing instrument, in combination with a tracker duct board having a series of ducts opening to the surface of the board; a valve bar having apertures adapted to register with the ducts at said surface; means for moving it for registration or non-registration of its said apertures; flexible tubes leading from a definite number of apertures of said valve bar for connection with a pneumatic action; a second valve bar having two apertures for each of a definite group of apertures of the first bar, constituting two sets adapted to register alternatively with those of said group of the first bar; a set of flexible tubes leading from one of said sets of apertures of the second bar for connection with the same pneumatic action to which the tubes of the first bar lead, and a second set of flexible tubes leading from the other set of apertures of the second bar for connection with a separate pneumatic action, and means for moving said second bar for alternative registration of its two sets of apertures with the apertures of said group of the first bar.

4. In an automatic music-playing instru-

ment, in combination with the tracker duct board having two series of ducts of different number leading to two different areas of the board's surface; separate principal valve bars for the two series having apertures adapted to register with the ducts separately and corresponding in number to the respective series of ducts; flexible tubes connecting a definite portion of the whole number of the apertures of the principal valve bar having the greater number with the corresponding apertures of the other principal valve bar, being a portion of the whole number of apertures of the latter bar, and adapted to connect them with the pneumatic action, said principal valve bar being adapted to be moved for cutting off and opening communication of the respective series of ducts with said pneumatic action; a secondary valve bar having apertures adapted to register with the remaining apertures of the principal valve bar having the lesser number; flexible tubes connecting a definite portion of the entire number of apertures of said secondary valve bar with the corresponding apertures of the principal valve bar having the greater number and adapted for connecting them with the pneumatic action; means for moving said secondary valve bar for registration or non-registration of its tube-connected apertures with those of the principal valve bar on which it is mounted, and means for closing at will the remaining apertures of said secondary valve bar and for closing the remaining apertures of the principal valve bar having the greater number.

5. In an automatic music-playing instrument, in combination with a tracker duct board having two series of ducts of different number leading to different areas of the board's surface; separate principal valve bars for the two series having apertures adapted to register with the ducts at said areas respectively, one or more secondary valve bars on each of the principal valve bars having apertures for registration with definite numbers of the corresponding apertures of said principal bars respectively; flexible ducts connecting certain corresponding apertures of the principal valve bars which are not covered by a secondary valve bar; like flexible ducts connecting any remaining uncovered apertures of the principal valve having the greater number with the corresponding apertures of the secondary valve bar which is on the other principal valve bar; flexible tubes connecting the remaining apertures of the last-mentioned secondary valve bar with the corresponding apertures of the other secondary valve bar, all said flexible tubes being adapted for connection with the pneumatic action, and means for operating said slide valve bars for registration or non-registration at will.

6. In an automatic music playing instrument, in combination with a tracker duct board having two series of ducts leading to different areas of the board's surface; said 5 series having different numbers of ducts; a group of valve bars for each series mounted one upon another, the first or principal valve bar being mounted on the duct board, covering and having apertures for register- 10 ing with the ducts thereof respectively, each succeeding valve bar covering and having apertures for registering with a part only of the apertures of the preceding bar; flexible tubes connecting all the uncovered apertures of the group of bars for the less 15 numerous series with the corresponding uncovered apertures of the other group and adapted for connecting the connected ducts of both series with a pneumatic action; 20 flexible ducts connected to the remaining uncovered apertures of said other group adapted for connecting them with a separate pneumatic action and means for moving the bars of both groups separately for reg- 25 istration and non-registration of their apertures with those of the contiguous bars and duct board.

7. In an automatic music playing instrument, in combination with a tracker duct 30 board having a series of ducts; a plurality of valve bars mounted one upon another, each bar after the first covering and having apertures for registering with a part only of the apertures of the preceding bar, the first 35 valve bar being mounted on the duct board covering and having apertures for register- 40 ing with all the apertures of the series; flexible tubes connected with the uncovered apertures of the several bars, and means for moving the bars separately for registration and non-registration of their apertures with those of the contiguous bars and duct board.

8. In an automatic music playing instrument, in combination with a tracker duct 45 board having two series of ducts of different number leading to different areas of the board's surface; a group of valve bars mounted one upon another for each series of ducts, the inner bar of each group being 50 mounted upon the duct board and having apertures for registering with all the duct mouths thereof, each bar after the first cov- 55 ering and having apertures for registering with a part only of the apertures of the preceding bar of the group, the outer bar of the group for the more numerous series of ducts having two sets of apertures corresponding to a limited group of apertures of the next inner bar; flexible tubes connected with all 60 the uncovered apertures of all the bars of both groups, the tubes from the uncovered apertures of the principal bar of the more 65 numerous series being connected with the tubes from the corresponding apertures of the other series, the remainder of the tubes

of said other or less numerous series being connected with one of the sets of tubes from said limited group, all the tubes connecting the corresponding ducts of the two series being provided with connections for one 70 pneumatic action, and all the tubes extending from one series only being adapted for connection with another pneumatic action.

9. In an automatic music playing instrument, in combination with a tracker board 75 having two series of ducts leading to different areas of the board's surface; valve bars for the two series having apertures to register with the ducts at said areas respectively 80 mounted upon the tracker board, and means also mounted on the tracker board for moving the valve bars for opening and closing the ducts.

10. In an automatic music playing instrument, in combination with a tracker board 85 having tracker ducts opening to the surface of the board; a plurality of valve bars mounted upon the tracker board for controlling separate groups of the ducts, and means also mounted on the tracker board 90 for moving said valve bars separately for opening and closing the respective groups of ducts.

11. In an automatic music playing instrument, in combination with the tracker 95 board, a plurality of valve bars mounted one upon another, the inner bar being mounted upon the duct board and having apertures for registering with all the duct mouths thereof, each bar after the first cov- 100 ering and having apertures for registering with a part only of the apertures of the preceding bar; flexible tubes connecting the uncovered apertures of all the bars for communication with a pneumatic action, and means mounted on the tracker bar for moving said valve bars separately for registration and non-registration of their apertures.

12. In an automatic music playing instrument, in combination with the tracker 110 board having two sets of ducts leading to different areas of the board's surface; a group of valve bars for each series of ducts, the valve bars of each group being mounted one upon another, the inner bar being mounted 115 upon the tracker board covering and having apertures for registering with the tracker board ducts, each bar after the first in each group covering and having apertures for registering with a part only of the apertures of the preceding bar; flexible tubes connected to the uncovered apertures of all the bars for leading to a pneumatic action, and means mounted on the tracker bar for 120 moving the several valve bars each independently of the remainder for registration and non-registration of its apertures.

13. In an automatic music playing instrument, in combination with a tracker board 125 having ducts opening to the surface of the

board; a plurality of valve bars supported on the tracker board for controlling the ducts in groups; a rotatable shaft also mounted on the tracker board transverse to the movement of the valve bars, and means on the shaft for actuating the several valve bars by the rotation of the shaft.

14. In an automatic music playing instrument, in combination with a tracker board mounted for adjustment bodily endwise; a plurality of valve bars supported on the tracker board having apertures for registration with the ducts thereof and movable separately for closing and opening the ducts in groups, and means mounted on the tracker board for operating such valve bars.

15. In an automatic music-playing instrument, in combination with a tracker-board having two series of ducts leading to ports in areas of the board's surface facing in different directions, bars mounted for bearing respectively upon said areas having apertures disposed therein for registration with the duct ports at said areas respectively.

16. In an automatic music-playing instrument, in combination with a tracker-board having two series of ducts leading to areas of the board's surface facing in different di-

rections, bars mounted for bearing upon said two areas having apertures disposed and spaced therein for registration with the duct ports at said respective areas, said bars and duct board being relatively positioned so that only one of the bars at a time has its apertures registering with the corresponding series of tracker duct ports.

17. In an automatic music-playing instrument, in combination with a tracker board having two series of ducts leading to differently facing areas of the board's surface; bars for the two series mounted for bearing upon said areas respectively, having apertures disposed and spaced to register with the duct ports at said respective areas, and means for relatively adjusting said bars and tracker board to register the apertures of the bars with the duct ports of the tracker board, one bar at a time.

In testimony whereof, I have hereunto set my hand, in the presence of two witnesses, at Chicago, Illinois, this 18th day of May, 1907.

MELVILLE CLARK.
